UNITED STATES PATENT OFFICE.

JOHN THOMAS McISAAC, OF EAST WEYMOUTH, MASSACHUSETTS, ASSIGNOR TO LEWIS A. CROSSETT CO., OF NORTH ABINGTON, MASSACHUSETTS, A CORPORATION OF MASSACHUSETTS.

ARCH SUPPORT.

1,404,624.

Specification of Letters Patent. Patented Jan. 24, 1922.

Application filed October 17, 1921. Serial No. 508,148.

To all whom it may concern:

Be it known that I, JOHN T. McISAAC, a citizen of the United States, residing at East Weymouth, in the county of Norfolk and

5 State of Massachusetts, have invented certain new and useful Improvements in Arch Supports; and I do hereby declare the following to be a full, clear, and exact description of the invention, such as will enable 10 others skilled in the art to which it appertains to make and use the same.

The present invention relates to the art of boots and shoes, and has more particular reference to the construction of arch support.

15 An object of the present invention is to afford a substantial support for the arch of the foot when bearing the weight of the body, but becoming at once pliable when the foot is flexed in the act of walking or bending, to permit of the natural freedom of the muscles; thus increasing the strength of the muscles and preventing the same from becoming atrophied or hardened, such as is the case when a rigid and unyielding arch 25 support is resorted to.

Another object is to provide an arch support which is combined in the shoe structure, so that the arch support is an inherent part of the shoe and is thus maintained at all 30 times in correct position relatively to the shoe and to the foot, and cannot be displaced or misapplied such as when separate arch supports are used.

The invention still further aims at the 35 provision of an arch support embodied in a shoe or boot construction which serves to reinforce the parts of the boot or shoe and which may be incorporated in such structure without material change in the detail construction and assemblage of the parts, and 40 which will not destroy the exterior configuration of the shoe but rather tend to hold it to its true and initial shape.

With the foregoing and other objects in 45 view, the invention will be more fully described hereinafter, and will be more particularly pointed out in the claims appended hereto.

In the drawings, wherein like symbols refer to like or corresponding parts throughout the several views,

Fig. 1 is a side elevation of a shoe, the upper thereof being in dotted lines and embodying an arch support constructed according to the present invention. 55

Fig. 2 is a detail top plan view of the outsole and heel part of a shoe constructed according to this invention.

Fig. 3 is a bottom plan view of the same, having the heel portion applied thereto. 60

Fig. 4 is a transverse section taken through the shoe substantially on the line 4—4 of Fig. 2, and looking in the direction of the indicating arrows.

Fig. 5 is a longitudinal section taken 65 through the lower part of a shoe substantially on the line 5—5 of Fig. 2.

Fig. 6 is a detail perspective view of the outsole, looking upon the upper side thereof.

Fig. 7 is a detail edge view of the outsole. 70

Fig. 8 is a longitudinal section through the outsole taken substantially on the line 8—8 of Fig. 6, and looking in the direction of the indicating arrows.

Fig. 9 is a detail perspective view of the 75 heel lifts constructed according to this invention and looking toward the upper surface thereof.

Fig. 10 is a bottom plan view of the same.

Fig. 11 is a side or edge view of the assembled heel lifts. 80

Fig. 12 is a longitudinal section there-through taken substantially on the line 12—12 of Fig. 9; and,

Fig. 13 is a longitudinal section similar to 85 Fig. 5, but with the parts in position such as they assume when in a finished shoe.

Referring to the drawings the present invention is illustrated as applied to one type of shoe, although it will be apparent that 90 the invention may be embodied in various types of boots and shoes according to the requirements of use and manufacture. In the present illustration 15 designates the upper portion of a shoe which is provided with an outsole 16, and the fore part of the outsole is of any suitable configuration and construction which is desired. This outsole 16, as best shown in Figs. 6, 7 and 8, is pressed or molded to form with the heel 85 part 17 depressed or off-set downwardly with respect to the general plane of the out- 100

sole and the shank portion 18 of the outsole is formed with a depression 19 struck downwardly from a point at the forward end of the heel part 17 and extending through substantially the major portion of the shank 18. This depression 19 is preferably of curved transverse section and gradually tapers in width and depth from the heel part 17 to its forward end, and at the latter merges into the general plane of the shank 18. This formation of the depression 19 provides a downwardly off-set reinforcement or strut for the shank 18 of the outsole, and this reinforcement is of a transverse width less than that of the shank 18, and is located midway between the lateral edges thereof.

The outsole is adapted to be secured to the upper portion 15 of the shoe in the usual manner with the exception of the heel part 17 which is off-set downwardly from the heel portion of the upper part 15, the space between the heel part 17 and the upper 15 receiving a filler 20 which, as best shown in Figs. 9 to 12 inclusive, comprises a plurality of lifts of leather or other suitable material forming the upper portion of the heel of the shoe. The lifts are provided with forwardly projecting tongues 21 which taper in width and thickness toward their outer ends and which conform to the depression 19 in the outsole for filling such depression and providing a reinforcing tongue which is capable of being flexed under conditions which bend the shank of the shoe. The outsole extends beneath the tongue 21 and the filler 20, and a heel piece 22 of rubber or other suitable material may be secured against the under side of the heel part 17 of the outsole to elevate the same to the desired height and complete the heel structure of the shoe. This filler 20, of leather, wood, fiber, steel or other suitable material, is encased within the depression 19 and completely hidden from view.

When the outsole with its heel and shank brace is attached to the upper portion 15 of the shoe, it is held in the finished position as shown in Figs. 1 and 13, and in which the shank 18 extends forwardly and downwardly at a slight angle, and the tongue 21 of the filler 20 is also flexed in such direction as to lie in the recess 19 and fill and reinforce the downwardly off-set brace which is struck from the outsole. This tongue 21 may be secured by glue, cement or the like to the inner face of the depressed support 19, and the layers of the tongue may be cemented or otherwise suitably secured together to form a compact filler which is flexible to such extent as to permit the action of the muscles in the arch of the foot and at the same time which is sufficiently rigid to tend

to support the arch and maintain the same in its proper position.

The upper surface of the filler 20 and its tongue forms a continuation of the upper face of the outsole and provides a relatively smooth surface for the insole and the foot.

The tongue or projection 21, being a part of the heel structure, is relatively rigid and cannot be permanently displaced, and thus forms a suitable reinforcement and filler for the depressed brace or strut of the outsole.

It is obvious that various changes and modifications may be made in the details of construction and design of the above specifically described embodiment of this invention without departing from the spirit thereof, such changes and modifications being restricted only by the scope of the following claims.

What is claimed is:

1. In a shoe, an outsole having a longitudinal depression in the shank thereof for maintaining the shank in shape and having a downwardly off-set heel part at the rear end of the shank, and a heel having lifts arranged above said heel part on the outsole and provided with forwardly projecting superposed tongues extending into the concavity of said depressed portion to reinforce the same and maintain said shank in shape, substantially as described.

2. In a shoe, the combination of an outsole having a depressed heel part and a depressed strut extending from the heel part into the shank of the outsole for reinforcing the shank, and a heel having an upper portion arranged above the heel part of the outsole and having a forwardly projecting tongue arranged to lie in the depression of the shank for reinforcing the latter and holding it to shape, substantially as described.

3. In a shoe, the combination of an outsole having a downwardly off-set heel part and a depressed strut extending from the heel part into the shank of the outsole, and a heel having an upper portion arranged above the heel part of the outsole and provided with a flexible forwardly extending tongue filling said depression in the shank of the outsole for yieldingly maintaining the shank of the outsole in shape, substantially as described.

4. In a shoe, the combination of an outsole having a portion of the shank thereof depressed downwardly to provide a reinforcement for the shank, and a heel part having a portion arranged above the outsole and provided with a yieldable filler projecting forwardly into the concavity of the depression in the shank of the outsole for yieldably supporting the shank and permitting flexing thereof under bending conditions, substantially as described.

5. In a shoe, the combination of an outsole having a downwardly depressed heel part and a forwardly extending depression in the shank portion of the outsole for reinforcing the shank portion, and a heel having a plurality of lifts secured together and provided with forwardly extending portions in super-

posed relation secured together to form a tongue, said tongue being shaped to the configuration of the depression in said shank 10 portion of the outsole for filling the same and yieldably supporting it under pressure of the foot, substantially as described.

JOHN THOMAS McISAAC.
